UNITED STATES PATENT OFFICE

2,265,381

EXHAUST MACHINE

Frank J. Malloy, Cleveland Heights, Ohio, assignor to General Electric Company, a corporation of New York

Application May 26, 1939, Serial No. 275,889

8 Claims. (CL 176—2)

My invention relates to machines for exhausting electric lamps and other similar devices comprising a sealed envelope, and more particularly to a multiple head exhaust machine for sealing such devices after they have been exhausted and filled with gas to a pressure greater than atmospheric.

The exhausting and gas filling of the envelope of such devices is done through a vitreous exhaust tube extending therefrom which is sealed or tipped off while the device is still connected to the exhaust machine. If the device is filled with gas to a pressure greater than atmospheric, some changes are required in the tipping operation so that this operation heretofore has not been done on exhaust machines having the usual high rates of production. One object of my invention is therefore to provide a rotary exhaust machine with tipping means suitable for closing and sealing devices filled with gas at pressures greater than atmospheric. Another object of my invention is to provide pinching jaws, for heating and squeezing the exhaust tube in order to seal it, of more rugged and lasting construction than heretofore.

A feature of my invention is the provision of pinching or tipping jaws in association with each head. This is an important feature since it greatly speeds up the operation of machines of this type by permitting heating of the pinching jaws and exhaust tube during rotation of the turret. Other objects and features of my invention will appear from the following detailed description of a species thereof and from the accompanying drawings.

In the drawings, Fig. 1 is a plan view of the front half of an exhaust machine comprising my invention with portions of two of the heads thereof removed; Fig. 2 is a vertical section through the half of the machine shown in Fig. 1 taken along the line 2—2 therein; Figs. 3 and 4 are plan and end views respectively, on an enlarged scale, of the tipping jaws of one of the heads of the machine; and Fig. 5 is a perspective view of the brushes and the wiring diagram of an electrical mechanism associated with each head.

Referring to the drawings, the machine comprises a plurality (sixteen) of heads 10 which are mounted at regular spaced intervals on the carrier or turret 11 in a circular path adjacent the periphery thereof. The turret 11 is indexed in a counter-clockwise direction in a manner causing each of the heads 10 to be carried in turn through a series of stations and, as shown in Fig. 2, is made up of the hub and outer sec-

tions 11' and 11'' respectively which are mounted on the hollow center column 12 of the machine. The hollow center column 12 provides the full support for the turret 11 and engages the ball bearing 13, which rests on the frame 14 of the machine, and the center post 15 which extends upward therethrough from another portion (not shown) of the frame 14.

In this particular instance, the device being exhausted and sealed is an incandescent lamp 16 of the type disclosed in Patent 2,148,314, D. K. Wright. The said lamps are introduced manually into the heads 10 by an operator stationed opposite station A. The lamp 16 comprises a sealed envelope formed by the vitreous cup 17 and cover glass 18 which function as a reflector and refractor respectively, a vitreous exhaust tube 19 which extends from the bottom or apex of the cup 17, and metal terminal elements 20 which are sealed to said cup 17 over openings therein at opposite sides of the exhaust tube 19.

In inserting the lamp 16 into the head 10 of the machine, the operator directs the exhaust tube 19 between tipping jaws 21 and 22 and into an open exhaust port 23 and rests the flange 24 of the cup 17 on asbestos pads 25 on the arms 26 extending from a holder 27. At this time, the tipping jaws 21 and 22 are separated and the exhaust port 23 is open so that the full weight of the lamp 16 is carried by the holder 27 which in turn rests on a radially extending arm 28 pivoted at its inner end on pin 29 extending from a bracket 30. The weight of these parts is not sufficient to cause movement of the arm 28 as the spring 31, which is located about the rod 32 between the holder 27 and the turret 11, is sufficiently strong to keep the holder 27 against the nuts 33—33' (Fig. 1) on the upper ends of said rod 32 and rod 34 respectively. Rod 34 is like rod 32 but is not provided, in this case, with a spring like spring 31. The bracket 30 is a fixed member, being fastened directly to the turret 11.

Following the insertion of the lamp 16, the turret 11 is indexed by mechanism (not shown) of the usual form and advances the head 10 into station B. Several operations are performed at this station, the first of which is due to the passage of the head of the stud 35 on the arm 28 into position below the roller 36 on the arm 37 extending from the stationary post 39 so that the arm 28 and the lamp 16 are lowered to a predetermined position. The exhaust port 23 is then closed on the exhaust tube 19 by movement of the arm 40 which is fastened to the vertical shaft 41 and which is turned so as to cause the roller

thereon to engage and turn the arm 42 of said exhaust port 23. The shaft 41 is operated by means (not shown) actuated by the main driving means of the machine in the customary manner and is supported in a like manner from post 39 by a portion of the frame 14 (not shown). The arm 42 extends from a threaded cap 43 on the body 44 of the exhaust port 23 which is turned so that the rubber washer 45 is compressed between it and said body 44 and seals the opening between said body 44 and the exhaust tube 19.

An exhausting operation also takes place at station B as the upper half 46 of the rotary valve which is located on the axis of rotation of the turret 11 and below the center section 11' thereof is turned so that it is aligned with separate portions of the lower half 47 of said valve to produce the exhausting operation. Each head 10 is represented by a passage in the upper half 46 of the rotary valve like that at 48 which is connected to the body 44 of the exhaust port by the pipe nipple 49, rubber tube 50, pipe 51, trap 52, pipe 53 and rubber tube 54. The passage 48 at this instant is located above a passage corresponding to that shown at 55 which is connected through the pipe nipple 56 to a source of vacuum and accordingly brings about the exhaustion of the lamp 16. The trap 52 provides a well and a screen 57 for catching foreign matter about to enter the exhaust port 23 and prevents such matter from entering and injuring the rotary valve or other parts of the exhaust system. The lower half 47 of the rotary valve in this instance is fastened directly to the frame 14, whereas the upper half 46 thereof is separated from the turret 11 by a plurality of springs 58 which press the halves 46 and 47 of the valve together and is engaged by the stud 59 extending from said turret 11. The above-mentioned parts of the machine are the only ones operating at station B although provisions are provided, in the form of an eccentrically pivoted cam 60, for squeezing the rubber tube 54 to close off the opening therethrough in the regular manner should a lamp be left out of the head 10 or a leaking lamp be carried thereby.

The succeeding indexing movement of the turret 11 which carries the head 10 into station C causes the stud 35 to be carried out from under the roller 36, the tipping jaws 21 and 22 to be closed on the exhaust tube 19, and brings about two successive changes in the exhaust cycle. The movement of the stud 35 from under the roller 36 does not result in movement of the arm 28 or the lamp 16 as the exhaust tube 19 is now gripped by the exhaust port 23 and the full expanding force of the spring 31 is used in keeping the holder 27 against the lamp 16, the arm 28 in a raised position and a slight tension in said exhaust tube 19. The tipping jaws 21 and 22 do not function at this time other than to close on the exhaust tube 19, and are described in full in combination with the tipping operation which occurs at succeeding stations. The change in the exhaust cycle is due to the rotation of the upper half 46 of the rotary valve and consists in: first, the termination of the exhaust operation as the passage 48 therein is carried over a solid portion in the lower half 47 thereof; second, the flushing of the lamp 16 with nitrogen as passage 61 is carried over a similar passage (not shown) in the lower half 47 which is connected to a source of nitrogen; and, third, the exhausting of said lamp 16 a second time as passage 48 takes a position over

another passage 55 and passage 61 is carried over a solid portion of said lower half 47 as station C is reached. The flushing nitrogen passes to the lamp 16 through the passage 61, pipe nipple 62, rubber tube 63, pipe 64, pipe 53 and rubber tube 54 and enters the system ahead of the trap 52 so that there is less danger of any foreign matter therein being blown into the lamp 16 and said system.

10 The exhausting operations at station C correspond to those occurring at station B and are the second exhausting operation of repeated exhausting and flushing operations carried on as the head 10 passes into station D and succeeding stations (not shown). However, as the finished lamp 16 is to be filled with argon in this instance, the final flushing operation is unlike the rest and is done with argon and is followed by the exhausting of the argon flush and the introduction of the argon filling. This latter operation is performed at a station opposite station B and preferably brings about the filling of the lamp 16 to a pressure higher than atmospheric.

15 The sealing and tipping of the exhaust tube 19 are the final operations performed by the machine and are preferably performed in the manner disclosed in Strickland application Serial No. 240,795, filed November 16, 1938, by the tipping jaws 21 and 22 carried by each head 10. The tipping jaws 21 and 22, as previously explained, close on the exhaust tube 19 during the indexing movement of the head 10 from station B to C but do not start to function to seal the tube until said head 10 reaches the station opposite station A. The jaws 21 and 22 are, as shown in Figs. 3 and 4, formed of a thin ribbon of metal, in this particular instance an alloy of nickel and chromium, and are each mounted on the metal arms 65 and 66 extending from one of the insulating blocks 67. The blocks 67, in turn, are fastened to the pins 68 which are pivoted in the ends of the arms 69 and 70 and rest, due to their own weight, on other portions of said arms 69 and 70. The arms 69 and 70 are pivoted on the pins 71 held by the bracket 30 and are constantly under the contracting influence of the spring 72 which extends between lugs on the bottom of each and tends to close them on the exhaust tube 19. At stations A and B, the jaws 21 and 22 are held open by the toggle system comprised of links 73-73 and the arm 74 as the vertical shaft 75 to which said arm 74 is fastened is turned by the arm 76 on the lower end thereof which then engages the cam 77 (indicated in Fig. 2) through the roller 78. The shaft 75 is held within a portion of the bracket 30 which extends through an opening in the turret 11. The cam 77 is held by a plurality of brackets 79, as indicated, and extends to a point midway between stations B and C where the tipping jaws 21 and 22 close.

20 The tipping operation starts as electric current is caused to flow through the jaws 21 and 22 so that they and the exhaust tube 19, with which they are in contact at this instant, are heated. This operation is brought about by the indexing movement which carries the brushes 80 into contact with separate sections of the rings 81 (Fig. 2) of the commutator 82. The ring sections of the commutator 82, which are engaged as the head 10 passes into the station (not shown) opposite station A, are connected to the regular line supply of electric current and are separated

from each other and the bolt 83, by which they are attached to the bracket 84 on the stationary center post 15 of the machine, by the insulating rings 85 and bushings 86. The brushes 80 in turn, as shown in Figs. 2 and 5, are each located in ways in the insulating block 87 which is supported by standard 88 and bracket 89 on the upper surface of the turret 11, and are caused to be pressed against the rings 81 of the commutator by the springs 90. The brushes 80 are held in the ways in the insulating block 87 by the insulating plate 91 which is attached thereto, and have flexible leads 92 extending therefrom which pass through the insulating blocks 93 closing off said ways. The blocks 93 are attached to the block 87 by the pins 94 which extend down therethrough and hold the springs 90 in place behind the brushes 80.

The electrical circuit energized by the movement of the brushes 80 includes the adjustable rheostat 95, the primary of the transformer 96 and the contacts 97 and 98 of the switch 99 which are then in engagement with each other. The secondary of the transformer 96 is connected through the wires 100 and 101 lying at opposite sides of the head 10 with the metal bars 102 attached to the upper ends of the jaws 21 and 22, and is included in a second circuit completed by the wire loop 103 which connects the metal arms 65—65 attached to the lower ends of said jaws 21 and 22.

Although the jaws 21 and 22 are heated to a relatively high temperature, the exhaust tube 19 is not completely sealed off when the head 10 comes into station E, and it is not until said head 10 reaches station F that this occurs and the switch 99 is opened and the primary current to the transformer 96 is interrupted so that the jaws 21 and 22 and the exhaust tube 19 are allowed to cool. The switch 99 may be of any form which will cause the circuit therethrough to be broken when the jaws 21 and 22 close to a predetermined point and the exhaust tube 19 is flattened a predetermined amount. This point, in this instance, is reached when the head of the bolt 104 (Fig. 3) carried by the arm 10 engages the actuating pin 105 of the switch 99 which applies pressure to the supporting strip 106 for the contact 98 and separates said contact 98 from contact 97. The pin 105 and the main body of the switch 99 are made from an insulating material and therefore do not interfere with the operation thereof.

As disclosed in the Strickland application hereinbefore referred to, the flattening of the exhaust tube 19 results in both a lateral and longitudinal expansion of said tube, the latter of which results in the upward movement of the lamp 16 and a rocking movement in the tipping jaws 21 and 22. A slight pull is exerted on the lamp 16 by the holder 27 and the arm 28 because of the spring 31 located therebelow, and the expanding force of said spring 31 carries the lamp 16, the holder 27 and the arm 28 upward. The rocking motion of the jaws 21 and 22 results in a more lengthy and positive seal and causes the blocks 67 to turn about the axes of the pins 68. The upper and lower halves of the faces of the tipping jaws 21 and 22 are offset slightly from each other, the lower halves 21'—22' being closer together so that the portion of the exhaust tube 19 engaging the said lower halves is flattened to a very thin section which can be easily broken. In this way, the excess end portion of the exhaust tube 19 can

be broken from the portion connected to the lamp 16 after said lamp has been removed from the machine without fear that the break will intersect the sealed portion thereof and cause a leak. As the U-shaped working portions of the jaws 21 and 22 are made from relatively thin metal and must be kept in shape to operate correctly, each is backed with a block 107 of an insulating material such as lava which butts against the arm 65 and is held in place thereby.

The next indexing movement of the turret 11 carries the head 10 into station G and carries the brushes 80 onto segments of the rings 81 of the commutator 82 which are not connected to the line and therefore breaks all electrical connections to the head 10. Station G, as well as the following station H, is not used for any other purpose than to allow the exhaust tube 19 to cool, although the arm 42 strikes the arm 108 during the movement and is turned so as to release that portion of the exhaust tube 19 held by the exhaust port 23.

The indexing movement of the head 10 from station H to J, however, brings about the separation of the tipping jaws 21 and 22 as the roller 18 on the arm 16 controlling their movement is then carried into engagement with the cam 71. Station J is the last in the operating cycle of the machine and permits the operator to remove the lamp 16 before the head 10 is again indexed into station A. In some instances, the exhaust tube 19 parts at the pinch and the end in the exhaust port 23 must be removed separately.

What I claim as new and desire to secure by Letters Patent of the United States is:

1. Apparatus for exhausting and gas filling a sealed envelope having a vitreous exhaust tube extending therefrom comprising a rotatable turret, a plurality of heads mounted adjacent the periphery of said turret and each comprising a port for receiving said exhaust tube, means for exhausting said envelope and filling it with gas through said port, mechanical pinching means mounted on each of said heads and arranged to engage a portion of said exhaust tube, means for heating the portion of said exhaust tube engaged by said pinching means during rotation of said turret, and means for actuating said pinching means to pinch and seal the said portion of the exhaust tube.

2. Apparatus for exhausting and gas filling a sealed envelope having a vitreous exhaust tube extending therefrom comprising a rotatable turret, a plurality of heads mounted adjacent the periphery of said turret and each comprising a port for receiving said exhaust tube, means for exhausting said envelope and filling it with gas through said port, metallic pinching jaws mounted on each of said heads and arranged to engage a portion of said exhaust tube at opposite sides, means operable by the rotation of said turret for causing an electrical current to be passed through said jaws to heat them and the portion of the exhaust tube engaged thereby during rotation of said turret, and means for actuating said jaws to pinch and seal the said portion of the exhaust tube.

3. Apparatus for exhausting and gas filling a sealed envelope having a vitreous exhaust tube extending therefrom comprising a rotatable turret, a plurality of heads mounted at spaced intervals adjacent the periphery of said turret, each of said heads comprising a port for receiving said exhaust tube, means for exhausting said envelope and filling it with a gas through said port, sup-

port means located above said exhaust port for supporting said envelope, said support means being arranged to be vertically movable, each of said heads having mounted thereon a pair of jaws arranged to engage opposite sides of said exhaust tube, said jaws being arranged for longitudinal movement with respect to said exhaust tube, means for heating said jaws and the adjacent portion of said exhaust tube during rotation of said turret, means for closing said jaws against said exhaust tube to pinch it and cause a longitudinal displacement thereof with a resulting vertical movement of the said jaws and the envelope support means.

4. Apparatus for exhausting and gas filling a sealed envelope having a vitreous exhaust tube extending therefrom comprising a rotatable turret, a concentrically arranged commutator on said turret, and a plurality of heads mounted at spaced intervals adjacent the periphery of said turret and each comprising a port for receiving said exhaust tube, means for exhausting said envelope and filling it with gas through said port, a pair of jaws mounted on each of said heads and arranged to engage opposite sides of said exhaust tube, means for supplying electric current to said jaws, means engaging the said commutator upon rotation of said turret for causing electric current to be supplied to said jaws to heat them sufficiently to soften said exhaust tube, means for actuating said jaws to pinch said tube and seal it, and means for interrupting the flow of electric current after said jaws have closed upon said tube a predetermined amount.

5. A device of the class described comprising a rotatable turret, a plurality of heads mounted at the periphery of said turret, each of said heads comprising a holder for supporting a sealed envelope having an exhaust tube depending therefrom, said holder being mounted to reciprocate substantially vertically a small amount, an exhaust port for receiving the lower end of said exhaust tube, spring means supporting said holder above said turret, means adjacent the path of travel of said holder arranged to temporarily engage said holder and lower it against the action of said spring means upon rotation of said turret to cause the end of said exhaust tube to further enter said port, mechanical pinching means associated with each said head and arranged to engage a portion of said exhaust tube, means for heating said portion of said exhaust tube, and means for actuating said pinching means to pinch and seal the said portion of the exhaust tube while said envelope is being urged upward by said spring means.

6. A device of the class described comprising a rotatable turret, a plurality of heads mounted at the periphery of said turret, each of said heads comprising a holder for supporting a sealed envelope having an exhaust tube depending therefrom, an arm supporting said holder and extending inwardly of said turret and being mounted on said turret at its inner end so as to pivot in a substantially vertical plane, an exhaust port for receiving the lower end of said exhaust tube, spring means supporting said holder above said turret, means adjacent the path of travel of said holder arranged to temporarily engage said holder and lower it against the action of said spring means upon rotation of said turret to cause the end of said exhaust tube to further enter said port, mechanical pinching means associated with each said head and arranged to engage a portion of said exhaust tube, means for heating said portion of said exhaust tube, and means for actuating said pinching means to pinch and seal the said portion of the exhaust tube while said envelope is being urged upward by said spring means.

7. In a device of the class described, the combination of a head comprising a port for receiving the vitreous exhaust tube of a sealed envelope, and means for pinching said exhaust tube comprising a pair of jaws formed of relatively thin approximately U-shaped ribbons of metal arranged to engage opposite sides of a portion of said exhaust tube, insulating blocks fitting closely within the said U-shaped ribbons as a backing therefor to prevent distortion thereof, means for passing an electric current through said jaws to heat them sufficiently to soften the portion of the exhaust tube engaged thereby, and means for actuating said jaws to pinch and seal the said portion of the exhaust tube.

8. In a device of the class described, the combination of a rotatable turret, a concentrically arranged commutator on said turret, and a plurality of heads mounted at spaced intervals adjacent the periphery of said turret for supporting envelopes having vitreous exhaust tubes extending therefrom, each of said heads comprising a port for receiving the exhaust tube of an envelope carried by said head, a pair of jaws mounted on each of said heads and arranged to engage opposite sides of the exhaust tube, means for supplying electrical energy to said jaws, means engaging the said commutator upon rotation of said turret for causing electrical energy to be supplied to said jaws to heat them sufficiently to soften said exhaust tube, and means for actuating said jaws to pinch said tube and seal it.

FRANK J. MALLOY.
